CLAIM

The ornamental design for a display screen with an animated graphical user interface, as shown and described.

DESCRIPTION

Cross reference is made to copending U.S. design patent application Ser. No. 29/767,040 entitled “Steering Wheel” by Wang et al., which was filed on even date herewith; U.S. design patent application Ser. No. 29/767,042 entitled “Display Screen with an Animated Graphical User Interface” by Wang et al., which was filed on even date herewith; U.S. design patent application Ser. No. 29/767,044 entitled “Display Screen with an Animated Graphical User Interface” by Wang et al., which was filed on even date herewith; U.S. design patent application Ser. No. 29/767,045 entitled “Display Screen with an Animated Graphical User Interface” by Wang et al., which was filed on even date herewith; and U.S. design patent application Ser. No. 29/767,047 entitled “Display Screen with an Animated Graphical User Interface” by Wang et al., which was filed on even date herewith.

FIG. 1 is a front view of a first image in a sequence for a display screen with an animated graphical user interface showing our new design;

FIG. 2 is a second image thereof;

FIG. 3 is a third image thereof;

FIG. 4 is a fourth image thereof; and,

FIG. 5 is a fifth image thereof.

The appearance of the animated graphical user interface sequentially transitions between the images shown in FIGS. 1-5. The process or period in which one image transitions to another forms no part of the claimed design. The broken lines shown in the drawings illustrate the display screen and portions of the graphical user interface that form no part of the claimed design.
